[57] CLAIM

The ornamental design for a extension cord socket system, as shown and described.

DESCRIPTION

FIG. 1 is a front elevation view of the extension cord socket system of the present invention;

FIG. 2 is a back elevation view of the extension cord socket system of FIG. 1;

FIG. 3 is a left side elevation view of the extension cord socket system of FIG. 1;

FIG. 4 is a right side elevation view of the extension cord socket system of FIG. 1;

FIG. 5 is a top plan view of the extension cord socket system of FIG. 1;

FIG. 6 is a bottom plan view of the extension cord socket system of FIG. 1; and,

FIG. 7 is a perspective view of the extension cord socket system of FIG. 1.

The cord is fragmentarily shown to indicate indefinite length.
